UNITED STATES PATENT OFFICE.

GEORGE W. DUDLEY AND WILLIAM J. JONES, OF WAYNESBOROUGH, VA.

VEHICLE-WHEEL.

SPECIFICATION forming part of Letters Patent No. 233,219, dated October 12, 1880.

Application filed March 16, 1880. (No model.)

To all whom it may concern:

Be it known that we, GEORGE W. DUDLEY and WILLIAM J. JONES, of Waynesborough, in the county of Augusta and State of Virginia, have invented a new and Improved 5 Elastic Wheel for Vehicles; and we do hereby declare that the following is a full, clear, and exact description of the same.

The main object of our invention is to form 10 a wheel-hub for vehicles in such manner that the wheel will yield sufficiently when undue and sudden strains or jars may come upon it to receive the force of the blow and shield the other portions of the vehicle from the destructive 15 effects of such action, as well as to afford ease and comfort of motion to the occupant; and the improvement consists in securing the inner ends of the spokes to rim-plates, to form a fixed and solid connection therewith, the said 20 rim-plates being loosely secured to the butt-flanges and box of the hub, so that it is free to move in a vertical plane, but prevented from moving laterally and limited in its vertical movement by an elastic packing interposed between 25 the inner ends of the spokes and the hub-box, which packing will form a cushion to receive the force of the blow, and thus protect the other portions of the carriage connected with and resting upon it; and the invention 30 consists in combining the butt and box cast together, the rim-plates separated by wedge-blocks secured to one of the plates and held together by bolts passing through the rim-plates and alternate wedge-blocks, an eye or 35 thimble keyed to the hub, the elastic packing interposed between the thimble-block and lower ends of the spokes, and the point or cap of the hub screwed onto the point of the box and held in place by a set-screw, as will be 40 hereinafter more fully described.

The object of the next part of our invention is to combine the above-described parts to form the hub, and to connect the rubber packing with the thimble in such manner that it may 45 readily be removed when desired; and the improvement consists in forming the thimble of two parts made conical upon their outer surfaces and held together at their smaller diameter by dowel-pins, to form a sectional dished 50 thimble, the conical sides of which will bear against the outer edges of the rubber and se-

curely clamp it, while by removing the sections the packing may be slipped off at once.

In the accompanying drawings, Figure 1 is a face view of the hub with the inner rim-plate 55 and hub-cap removed; Fig. 2, a longitudinal section through the hub; Fig. 3, an elevation of the thimble with its sections detached.

In the construction of our improved wheel-hub the butt A and box B are preferably cast 60 together in a single piece. The box B is provided with a screw-thread to receive the cap or hub-point C, which is screwed upon it and held in position by a set-screw, c.

The ends of the spokes D are firmly clamped 65 between the rim-plates E F, the inner plate, E, having wedge-blocks e, of oval cross-section, projecting from the face of the plate at equal distances apart. The sides of the wedge-blocks e are rounded, and the sides of the meeting or 70 inner ends of the spokes are correspondingly dished, to exactly fill the double concave spaces between the wedge-blocks, so that the spokes may be applied to the rim-plate E laterally, and all be held separately in position and 75 firmly locked together to receive any vertical pressure that may come upon them. A slight lateral movement of either of the spokes will readily disengage it without displacing the remainder.

In order to firmly hold the spokes in their sockets laterally, an outer rim-plate, F, corresponding in outline with the plate E, except that wedge-blocks are not formed upon its face, is firmly bolted against the sides of the 85 wedge-blocks and outer sides of the meeting ends of the spokes, and is firmly clamped in such position by bolts G, that pass through both rim-plates, as well as through each alternate wedge-block, thus giving the bolts a firm 90 bearing-surface, to closely clamp the plates and prevent the inner plate from slipping upon the ends of the wedge-blocks without passing through the spokes to weaken them.

The hub-box B has its inner surface smoothly 95 turned to receive a thimble, H, of peculiar construction, and is provided with a key, h, projecting from its outer surface to fit snugly into a corresponding groove or key-seat in the wall of the thimble, so that the thimble and hub-block will revolve together, but may be readily disconnected. The thimble H is made

in two conical sections, $H'H^2$, Fig. 3, the smaller diameters of which are placed together and to form a dished face to the thimble, and are prevented from turning upon the hub-box either 5 separately or together by the key h above described. Dowel-pins $h' h'$ may also be employed to hold the sections in proper relation to each other, if desired.

When the thimble is in place upon the hub-box and the rim-plate and spokes are clamped together in place, an annular space will be left 10 between the rim-plates forming the sides, and between the thimble and meeting ends of spokes with their wedge-blocks forming the inner and 15 outer periphery thereof. This space is filled with rubber or other elastic material, I, closely packed and forced in with a pressure that will cause it to withstand without yielding the weight of the load that is to come upon it, so 20 that the axle is retained in the center of the wheel when at rest. An unusual shock will temporarily displace it, and the packing will thereby act as a cushion to relieve the other portions of the vehicle from strain. The packing 25 will, of course, have sufficient elasticity to restore the wheel and axle to their proper relative positions.

The dished surface of the thimble will bind the packing upon its lower and outer edges, 30 and because of its double conical shape will serve to compress it considerably. As the thimble is made in interlocking detachable sections, they may be readily removed from the hub-box when it is to be withdrawn from the hub- 35

Wheels provided with hubs of the above description are well suited for vehicles that are to be driven over rough roads, and will be exceedingly well adapted to the road-bed of city streets that are paved with cobble-stones or 40 other roughened stone surface.

What we claim as new is—

1. The combination, with the elastic packing and the hub-box provided with butt-flanges, of the spokes D and rim-plates E and F, one 45 having the inner projections, e, and both cutout at the center, to allow the requisite movement radially when the pressure on the rim of the wheel causes compression of the packing, as shown.

2. The combination of the butt A, box B, cap C, rim-plates E F, wedge-blocks e, spokes D, packing I, and thimble H, fitting upon the box B and prevented from turning thereon by the key h, substantially as and for the purpose 55 described.

3. The combination, in an elastic vehicle-wheel hub, of the butt, box, cup, rim-plates, packing, and thimble H, formed of two conical sections placed with their smaller ends together, to form a dished groove in the surface of the thimble, to be held together by dowel-pins, so that they may be separated to readily remove the packing from between them, substantially as described.

GEORGE WILSON DUDLEY.
WILLIAM JOSEPH JONES.
